UNITED STATES PATENT OFFICE.

NEAL T. NASH, OF HINTON, IOWA, ASSIGNOR TO MINNIE M. NASH, OF HINTON, IOWA.

COMPRESSED-AIR AUTO-STARTER.

1,264,118.

Specification of Letters Patent. Patented Apr. 23, 1918.

Application filed September 21, 1914. Serial No. 862,807.

To all whom it may concern:

Be it known that I, NEAL T. NASH, a citizen of the United States, residing at Hinton, in the county of Plymouth, State of Iowa, have invented certain new and useful Improvements in Compressed-Air Auto-Starters; and I do hereby declare the following to be a full, clear, and exact description of the invention, such as will enable others skilled in the art to which it appertains to make and use the same.

This invention relates to starting devices for internal combustion engines and has special reference to a fluid operated starter for automobiles.

The principal object of the invention is to improve and simplify the general construction of devices of this character.

With the above and other objects in view, the invention consists in general of certain details of construction and combination of parts hereinafter fully described, illustrated in the accompanying drawings, and specifically claimed.

In the accompanying drawing, like characters of reference indicate like parts in the several views, and:

Figure 1 is a plan view of an automobile showing the starter applied thereto.

Fig. 2 is a detail side elevation of the arrangement shown in Fig. 1.

Fig. 3 is a section on the line 3—3 of Fig. 1.

Fig. 4 is an enlarged detail view of the clutch mechanism and gearing for connecting the engine shaft with the shaft of the starter.

Fig. 5 is a detail vertical section through the starting engine.

Fig. 6 is a section on the line 6—6 of Fig. 5.

Fig. 7 is a detail section on the line 7—7 of Fig. 5, the section showing eccentric and crank of the starter shaft when the piston attached to said crank is in its highest position.

Fig. 8 is a detail view, showing a controlling valve for the outlet pipe.

In carrying out the objects of the invention the automobile's chassis, which is indicated at 10 has supported thereon an air tank 11, which is connected by a pipe 12 with branch pipes 13 and 14. Located in the pipe 13 is a check valve 20 which opens toward the tank 11, and at a farther distance from the tank 11 is a T-joint having

one arm open to the atmosphere and in the latter is disposed a gate valve 15 which is manually operable by the levers 17 and 18. In the branch pipe 14 there is located a 60 gate valve 15 which is operable by means of the hand lever 16, and at a farther distance from the tank 11 the pipe is also provided with a T-joint 21, within the arm 56 of which is mounted a check valve, 65 and it should also be noted that the arm 56 is open to the atmosphere.

The ordinary gas engine 22 is used with the automobile and on the driving shaft or crank shaft 23 of this engine are spaced 70 the gears 24 and 25. Mounted on the chassis adjacent the shaft 23 is the starting engine. The starter comprises a crank case 26 wherein is supported a crank shaft 27.

On the crank shaft 27 are arranged the 75 gears 28 and 29 which mesh respectively with the gears 24 and 25. Each of these gears 28 and 29 is mounted loosely on said shaft and splined to the shaft is a double cone clutch member 30 arranged to co-operate with clutch members 31 and 31' carried on the respective gears 28 and 29. The member 30 is provided with the usual shipper groove 32 controlled by a shipper 33 by a link 34 with a lever 35 arranged adjacent the operator's seat.

It will be observed that by moving the member 30 in one direction or the other, one of the gears on the shaft 27 may be clutched to the said shaft and thus the shaft 90 be connected operatively to the shaft 23.

Extending upward from the crank case 26 are guides 36 and 36' wherein are mounted cross-heads 37 and 37' connected by rods 38 and 38' with the cranks 39 and 39' of 95 said shaft 27, said cranks being preferably arranged quartering. Supported on the upper ends of the guides 36 and 36' are cylinders 40 and 40' wherein are mounted pistons 41 and 41' connected to the cross-heads 37 100 and 37' by piston rods 42 and 42'. Between the cylinders 40 and 40' are arranged cylindrical valve chambers 43 and 43' which are connected with the cylinders 40 and 40' by ports 44 and 44' arranged at each end of 105 said cylinders. Within each of the chambers 43 and 43' are spaced pistons 45 and 45' connected by valve stems 46 and 46', the pistons forming the working parts of the respective valve. These valve stems extend 110 downward through stuffing boxes 47 and 47' and guides 48 and 48' and are connected by

eccentric arms 49 and 49' to eccentric straps 50 and 50' surrounding eccentrics 51 keyed on the shaft 27. At the end of the pipe 13 branches 52 and 52' are provided which 5 communicate with ports 53 and 53' leading to the respective valve chambers 43 and 43'.

Entered into the intermediate points in the valve cylinders are the ports 54 which are connected to a suitable pipe 55 which 10 acts as a continuation of the branch pipe 14 leading from the air tank 11.

In order to render the starting apparatus operative it is obviously necessary to primarily charge the tank 11 with compressed 15 air. Therefore, the engine 22 is started in the usual manner and the gate valves 15 and 15' are closed. The clutch mechanism is then operated so that the large gear 28 is locked to the shaft 27, so that the engine is 20 geared to the starting engine. Then, the starting engine being driven by the internal combustion engine, air is drawn into the branch 56, through the check valve in the T-joint 21, through the pipe 55 into the 25 starting engine, then into the pipe 13 past the check 20 and into the tank 11. This pumping action may be continued until the tank 11 is suitably charged. When the apparatus is to be used to start the engine 22, 30 the valves 15 and 15' are both thrown to open position, so that air may flow from the tank 11 to the pipe 12 and to the pipe 14, by way of the pipe 15 into the air valve cylinders of the starting engine, thereby operating 35 the latter and exhausting by way of the pipe 14 and the T which contains the valve 15' to the atmosphere. Obviously since the pressure in the tank 11 is greater than the atmospheric pressure, the check 20 will remain inactive during the starting operation. 40 Of course, when the device is used as a starter, the lever 35 is moved to clutch the small gear 29 to the shaft 27, so that a suitable gear ratio will be set up between the 45 starting engine and the internal combustion engine.

The operation of the crank shaft 27 under

the influence of the compressed air will start the engine 22. After starting the engine the gears on 27 are unclutched and the lever 16 moves to cut off air from the starter. Of course at any time during the operation of the engine 22 the first part of the operation above described may be repeated to fill the tank 11.

There has thus been provided a simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such 65 as come properly within the scope of the claim.

Having thus described the invention, what is claimed as new is:

In an automobile starting mechanism, the 70 combination of a pair of cylinders, a valve casing extending parallel with each cylinder, a pair of rigidly connected valves in each casing, each casing having an inlet port between said valves, a pair of ports communicating with its corresponding cylinder and adapted to be alternately uncovered by 75 said valves, and exhaust ports at opposite ends of the casings, whereby to exhaust said cylinders through said inlet ports on the return strokes of said valves, an air tank, a conduit connecting said inlet port to said tank, a second conduit branched from the first conduit and connecting said exhaust ports to said tank and means for controlling 80 said connecting means whereby to pump air through said cylinders.

In testimony whereof I affix my signature, in the presence of two witnesses.

NEAL T. NASH.
